UNITED STATES PATENT OFFICE.

ALBERT FURNISS, OF WEST MERIDEN, ASSIGNOR TO MYRON H. KINSLEY,
OF WALLINGFORD, CONNECTICUT.

DESIGN FOR SPOON-HANDLE.

SPECIFICATION forming part of Design No. 11,661, dated March 2, 1880.

Application filed February 2, 1880. Term of patent 7 years.

To all whom it may concern:

Be it known that I, ALBERT FURNISS, of West Meriden, in the county of New Haven and State of Connecticut, have invented a new 5 Design for Fork and Spoon Handles; and I do hereby declare the following, when taken in connection with the accompanying drawing and the letters of reference marked thereon, to be a full, clear, and exact description of the same, 10 and which said drawing constitutes part of this specification, and represents, in face view, the design.

This invention relates to a design for the handles of spoons, forks, and like articles of 15 table-service; and it consists in the ornamentation of the handle, as hereinafter described, and shown in the accompanying illustration.

The outline of the handle is that known as "lancet shape." Across the handle, near the 20 bowl, is a raised bead, *a*, and above this, at the point where the expansion of the handle begins, is a transverse ornamental band, *b*. Between the points *a* *b* is a central longitudi-

nal raised bead, *c*. Above the band *b* double beads *d* start from each side, and, curved upward, meet at the center; and above these beads *d* are other similar beads, *e*, running parallel to the beads *d*, and terminating in a point at the center in the broad part of the handle. The space between the beads *d* *e* is filled with 25 floriated vine. On the face of the handle a spear of wheat springs from the band *b* and extends up between the beads *d* *d*. The body 30 of the handle is surrounded by a bead, *f*.

I claim—

The design for a spoon-handle, consisting of the transverse bands *a* *b*, the curved beads *d* *e*, and the ornamentation between the band *b* and the beads *d* and between the beads *d* and *e*, as 35 described, and shown in the accompanying illustration.

ALBERT FURNISS.
